A CORPORATION OF CONNECTICUT.

ELECTRICAL SWITCH AND SOCKET-KEY.

No. 839,519.

Specification of Letters Patent.

Patented Dec. 25, 1906.

Application filed February 15, 1906. Serial No. 301,288.

To all whom it may concern:

Be it known that I, HERBERT L. SMITH, a citizen of the United States, residing at Bridgeport, county of Fairfield, State of Connecticut, have invented a new and useful 5 Electrical Switch and Socket-Key, of which the following is a specification.

This invention has for its object to provide 10 electrical switch and socket-keys which shall be simple and inexpensive to produce, neat and attractive in appearance, which may be molded from either a vulcanizable or a non-vulcanizable compound, and which shall be so constructed as to render breakage of the 15 keys and twisting of the keys off from the mandrels or shanks practically impossible under the ordinary conditions of use.

Heretofore it has been the practice to flatten 20 the key ends of the mandrels before molding the keys thereon. Keys made in this manner, however, have not proved satisfactory, owing to the fact that unless made from a very tough compound, they were liable to break easily if dropped and broke frequently 25 in use, and, furthermore, that no matter from what kind of a compound they were molded they frequently became loose and turned on the mandrels or shanks, thus rendering the keys useless and requiring that 30 new ones be provided.

My present invention wholly overcomes 35 these objections and enables me to provide electrical switch and socket-keys which, owing to the peculiar construction of the inner 40 ends of the mandrels or shanks, may be molded from relatively inexpensive compounds, thus effecting a great saving in the cost of production and producing keys that are neat and attractive in appearance, will 45 not break easily when dropped, will not break under the ordinary conditions of use, and cannot turn or become loose on the mandrels or shanks.

With these and other objects in view I have 50 devised the novel switch and socket-key of which the following description, in connection with the accompanying drawing, is a specification, reference characters being used to indicate the several parts.

Figure 1 is an elevation of an electrical 55 switch or socket-key embodying my novel improvement; Fig. 2, a section of the key in the direction of its greater dimension, showing the mandrel in side elevation; and Fig. 3

is a section at right angles to the section-line 55 in Fig. 2, showing the split in the key end of the mandrel and the manner in which the separated parts are bent outward away from each other.

10 denotes the key proper and 11 the mandrel or shank, which is made from wire of suitable size cut into suitable lengths. The novel feature of the invention is that I split the key end of the mandrel centrally and bend the separated parts outward in opposite directions in the plane of the cut, as clearly shown in Figs. 2 and 3, the cut being indicated by 12 and the separated parts of the end of the mandrel by 13. Having prepared the mandrels by splitting the ends and bending the parts outward in opposite directions in the plane of the cut, the key is molded thereon in the usual manner. Owing to the fact, however, that the separated parts of the end of the mandrel extend well outward 75 into the wings of the key, as clearly shown in Fig. 2, it is rendered impossible for the key to turn on the mandrel in use and practically impossible for the key to break, even when dropped or when subjected to the hardest 80 kind of usage.

The bending outward of the split parts of the key in the plane of the cut, as described, results in the portion which extends into each wing being only one-half the thickness 85 of the portion which forms the stem or shank. Therefore the wings of the key can be very thin, and still not result in exposure of the edges of the outwardly-bent portions of the reinforce. 90

Having thus described my invention, I claim—

Switch and socket-keys comprising a mandrel having the key end split and the parts thereof bent outward in opposite directions 95 in the plane of the cut, and a key formed from a suitable compound and molded thereon, the separated parts of the end of the mandrel extending well outward into the wings 100 of the key, substantially as described, for the purpose specified.

In testimony whereof I affix my signature in presence of two witnesses.

HERBERT L. SMITH.
